Primary Examiner—Susan J. Lucas*Assistant Examiner*—M. Brown*Attorney, Agent, or Firm*—Cox & Smith Incorporated[57] **CLAIM**

The ornamental design for a rack for pickup trucks, as shown and described.

DESCRIPTION

FIG. 1 is a perspective view of a rack for pickup trucks showing my new design, the broken lines are shown for illustrative purposes only and form no part of the claim design.

FIG. 2 is a side view of FIG. 1;

FIG. 3 is a top plan view of the rack embodying this invention;

FIG. 4 is a bottom plan view of a rack embodying this invention;

FIG. 5 is a right side elevational view of a rack embodying this invention and the left side elevational view is the same as FIG. 5;

FIG. 6 is a front elevational view of the rack embodying this invention; and,

FIG. 7 is a rear elevational view of the rack embodying this invention.
